UNITED STATES PATENT OFFICE.

WILLIAM H. DOANE, OF CINCINNATI, OHIO.

SPOKE-THROATING MACHINE.

SPECIFICATION forming part of Letters Patent No. 340,909, dated April 27, 1886.

Application filed January 30, 1886. Serial No. 190,288. (No model.)

To all whom it may concern:
Be it known that I, WILLIAM H. DOANE, a citizen of the United States, residing at Cincinnati, in the county of Hamilton and State 5 of Ohio, have invented certain new and useful Improvements in Spoke-Throating Machines; and I do hereby declare the following to be a full, clear, and exact description of the invention, such as will enable others skilled in 10 the art to which it appertains to make and use the same.

Spoke-throating machines are known which throat spokes on both sides simultaneously by means of two oscillating cutter-heads, no reversal of the spoke being required. Other 15 spoke-throating machines are known which are adapted to throat the two sides of a spoke successively by means of two fixed cutter-heads, but which require the reversal of the 20 spoke after one side has been throated and before the other side can be throated.

My invention consists, as a whole, of a machine so organized with two fixed cutter-heads that it can throat the two sides of a spoke successively without requiring the reversal of the 25 spoke.

In order that my invention may be clearly understood, I have illustrated in the annexed drawings, and will proceed to describe, a practical form thereof.

Figure 1 represents a front elevation of this spoke-throating machine. Fig. 2 represents a side elevation thereof. Fig. 3 represents a plan of the same. Fig. 4 represents a front elevation of a portion of the machine, and 35 illustrates how the spoke is held in traversing it past the respective cutter-heads.

The same letters of reference indicate identical parts in all the figures.
40 In the machine shown in the drawings one of the cutter-heads is arranged in advance of the other, so that both sides of the spoke can be throated during a single pass of the spoke through the machine. This is an advantageous arrangement, but not a primary necessity. Cutter-head A is secured to a horizontal shaft, A', which is journaled in bearings of a slide, A'', mounted on vertical guide-rails c on the front side of frame or column C. Slide A'' is 45 held in position vertically, and can be adjusted vertically by a screw, A''. Cutter-head B is secured to a horizontal shaft, B', which is

journaled in bearings of a slide, B'', mounted on vertical guide-rails c' on the front side of an upward extension, C', of column C. Slide 55 B'' is held in position vertically, and can be adjusted vertically by a screw, B''. Slide A'' has a bracket-arm, a, projecting alongside cutter-head A. An angle-iron or foot, a', is fitted in a horizontal guideway on bracket-arm a, and 60 is secured thereto by a clamping-bolt, a'', which passes through a horizontal slot in the sole-plate of the foot, so that the latter can be adjusted horizontally along the bracket-arm, in order to bring the heel-plate of the foot to the 65 desired position with reference to the outer end of the cutter-head A, which end it faces. A spoke-guide, D, is secured to the heel-plate of foot a' by clamping-screws d d, which pass through vertical slots d d' in the spoke-guide, 70 so that the latter may be vertically adjusted to bring its curved upper edge to the required position with reference to cutter-head A. Slide B'' has a similar bracket-arm, b, on which a similar foot, b', is adjustably mounted, the 75 same as foot a' is mounted, and a similar spoke-guide, E, is adjustably secured to the heel-plate of foot b', in reverse position, however, so that the lower edge forms the spoke-guiding edge. Cutter-head shafts A' and B' 80 are provided with pulleys for driving them in opposite directions by suitable belt gearing.

The spoke is supported upon and fed through the machine by the spoke-carriage F, which is hinged on the fixed rod G, on which it also 85 slides. Rod G is secured to posts G' G', which are in turn secured in sockets or eyes on arms C' and C'' of column C. The posts G' are secured by set-screws, so that they may be adjusted to raise the rod G to the proper height— 90 namely, to such height that its axis will lie in a horizontal plane about midway between the respective horizontal planes of the axes of the cutter-heads. This arrangement of the rod G with reference to the axes of the cutter-heads 95 is important, because it insures a like, though reverse, presentation of the spoke to the respective cutter-heads, so that the spoke will be throated alike on both sides.

In the machine shown the cutter-heads are 100 so close together that the rear end of spoke-guide D projects beyond the front edge of spoke-guide E, in consequence of which a vertical clearance-space must be left between the

spoke-guides, in order that the spoke may be lifted from spoke-guide D to a sufficient height to permit it to properly follow spoke-guide E. To provide for shaping the spokes alike under these circumstances, the cutter-heads are so adjusted that the spoke, in presenting it to the lower cutter-head, will have a downward inclination alike in degree to that of its upward inclination on presentation to the upper cutter-head, as indicated in Fig. 4. It is obvious that cutter-head A may be placed so far in advance of cutter-head B that the spoke can be presented horizontally to each. In all cases the cutter-heads are so arranged with reference to the spoke-carriage as to be on opposite sides of the plane or path along which the carriage moves the spoke.

The spoke-carriage is provided with a spoke-clamping lever, H, for clamping the tenon of the spoke down on the bar f of the carriage, and with the usual adjustable knee, I, against which the body of the spoke rests. A handle, f', on the spoke-carriage near knee I projects under the spoke, so that the operator in pushing the carriage forward may hold the spoke and handle grasped with his right hand, while he holds the clamping lever depressed with his left hand. A rail, C⁴, is provided on column C, for supporting the free side of the spoke-carriage in either of its extreme positions. The spoke-carriage may be counterbalanced by a weighted arm, F', as shown.

The machine is adjusted to different sizes of spokes by vertical adjustments of the cutter-head slides. It will be understood that with cutter-heads of given form the shape of the throats is determined in part by the spoke-guides, and in part by the transverse contour of the spoke where it traverses the spoke-guides.

I do not confine myself to the particular style of spoke-carriage shown and described, as other known styles of spoke-carriages,

whether hinged or not, can be readily substituted for the one illustrated; nor do I confine myself, primarily, to other details of construction, because they may be much varied without departure from the fundamental characteristics of my invention as generally set forth in the recital at the beginning of this specification, and distinctly pointed out in the first of the ensuing claims.

I claim as my invention—

1. The combination, substantially as before set forth, of a spoke-carriage, two fixed cutter-heads, which are arranged, respectively, on opposite sides of the plane or path along which the spoke is moved by said carriage, and a fixed spoke-guide on each cutter-head slide, whereby the two sides of a spoke can be threated ed successively without reversing it.

2. The combination, substantially as before set forth, of a spoke-carriage, two fixed cutter-heads, which are arranged one in advance of the other, and respectively on opposite sides of the plane or path along which the spoke is moved by said carriage, and a fixed spoke-guide on each cutter-head slide, whereby the two sides of a spoke can be threated successively at a single pass and without reversing the spoke.

3. The combination, substantially as before set forth, of a hinged spoke-carriage, two fixed horizontal cutter-heads, which are arranged, respectively, on opposite sides of the plane or path along which the spoke is moved by said carriage, a screw applied to the supporting-slide of each cutter-head for vertically adjusting the same, and a fixed spoke-guide on each cutter-head slide.

In testimony whereof I affix my signature in presence of two witnesses.

WILLIAM H. DOANE.
